LAST LINE INDICATING ATTACHMENT
FOR TYPEWRITERS

Adolphus D. Thomas, San Bernardino, Calif.

Application October 12, 1939, Serial No. 299,198

3 Claims. (Cl. 197—189)

This invention relates to a means or attachment to a typewriter which will give an audible or other signal or indication when the last line desired for typing is reached, to the end that typing will cease at the proper distance from the bottom of the page and the pages will be uniform, and sufficient space left in which to number or otherwise distinguish them.

More specifically, it is aimed to provide a device of the present character which is operable by the turning of the platen of the typewriter and has novel means adapted to be manually set according to the distance desired for the last line from the top of the sheet.

I further aim to provide a structure of the present character in the nature of an attachment to existing typewriters, wherein the parts are operable by spring controlled gearing and wherein the parts may be readily reset.

Various additional objects and advantages will become apparent from a consideration of the description following taken in connection with accompanying drawings illustrating an operative embodiment.

In said drawings:

Figure 1 is a view showing my improvements in plan and as attached to a typewriter, the latter being shown fragmentarily;

Figure 2 is an end elevation of the parts of Figure 1;

Figure 3 is a vertical section taken on the plane of line 3—3 of Figure 2;

Figure 4 is an elevation looking interiorly of the attachment from one side, the cover plate being removed;

Figure 5 is a vertical section taken on the line 5—5 of Figure 3;

Figure 6 is a detail section taken on the plane of line 6—6 of Figure 3;

Figure 7 is a horizontal section taken on the plane of line 7—7 of Figure 4;

Figure 8 is a horizontal section taken on the plane of line 8—8 of Figure 4;

Figure 9 is a perspective of the clapper for the bell, and

Figure 10 is a perspective of the trip member associated with the clapper.

Referring specifically to the drawings wherein like reference characters designate like or similar parts, the frame of a typewriter carriage is fragmentarily shown at 10 mounting the platen at 11 in the usual manner, that is by means of a shaft 12 journaled therein.

The parts constituting my invention are mounted by a generally cylindrical housing or

casing 13 which includes a container section 14 having an end wall 15 vertically disposed, and a cylindrical wall 16. It also has a removable closure section 17 constituting an end wall which is fastened detachably in place as by means of a screw 18 engaging a bracket 19 suitably mounted on the wall 16. Such casing 13 is attached to the carriage frame 10 in any suitable manner, preferably removably by means of a bracket 20 screwed at 21 to the carriage frame 10 and bolted at 22, detachably to the wall 15.

Attached to the platen shaft 12 in axial alignment therewith is an extension or operating shaft 23 for my attachment. This shaft may have a sleeve at 24, rigidly but removably coupled to 15 shaft 12 by means of screws 25. Shaft 23 extends through the walls 15 and 17, in which they are journaled, and in the former is a bearing as at 26. Shaft 23 may be operated manually like the shaft 12 of the typewriter and at its outer end preferably has a knob 27.

Shaft 23 carries a gear or pinion 28 interiorly of the housing 13 which is enmeshed with the peripheral teeth 29 of a gear wheel 30, the latter preferably being skeletonized as shown. Said gear wheel 30 is journaled on an arbor or pin 31 extending longitudinally and substantially centrally of the housing 13 and rigidly from a reset lever 32 which is pivoted by means of a screw 33, or otherwise, to the inner end wall 15 of housing 30 13. Such lever 32 extends exteriorly of the housing 13 through a peripheral slot 34 in wall 16 of a length to permit and limit its movement. A contractile spiral or clock spring 35 has one end fastened at 36 to the gear wheel 30 and its other end fastened to a short sleeve 37 which in turn is fastened by a pin 38, rigidly but removably to the arbor or pin 31. In this manner, the teeth 29 of gear wheel 30 are normally enmeshed with the teeth of the pinion 28 but are capable of demeshing with said pinion by operation of the reset lever 32 since the latter swings on an axis eccentric to the gear wheel 30.

When the gear wheel 30 is out of mesh with the pinion 28, the spring 35 returns the same to normal position in which a lug 39 engages a stop 40 which is preferably in the form of a leaf spring anchored in any suitable manner at 41 to the inner end wall 15 and having an arcuate portion 42 directly engaging said lug 39.

The reset lever 32 is constantly urged to the position in which teeth 28 are enmeshed with the pinion 28 in a suitable manner, as by means of an arm 43 of a generally U-shaped spring 44,

expanding against the same and anchored as at 45, to the inner end wall 16.

Wall or closure 17 carries a bell or other audible signal member 46 interiorly of the housing 13 and the same is adapted to be sounded through the operation of the platen 11, gearing described, and novel trip means and clapper adjustably mounted on the peripheral wall 16. To this end, an arcuate indicator strip or band is provided at 10 47 on the periphery of wall 16, having one end upturned as at 48 to facilitate manual manipulation. Such strip 47 has indications or calibrations 49 thereon proportioned with respect to the rotation of platen 11, to indicate in inches, the 15 travel of a sheet of paper with the platen, as the sheet of paper passes through the typewriting machine, incidental to typewriting successive lines thereon. Parallel to the strip 47, is an arcuate plate 50, arranged interiorly of the housing 20 and in engagement with the inner surface of wall 16 and rigidly connected with the strip or band 47 as by means of a screw 51, preferably rigid with strip 47 and extending through an elongated slot 52 peripherally through the wall 25 16 which is engaged by a nut 53, bearing against the plate 50. A guide pin or lug 54, may extend inwardly from the strip 47 and operate in the slot 52, with a view to preventing tendency of the strip to turn on the member 51 or to otherwise 30 displace.

A bracket 55 depends from the plate 50 and rigidly mounts a pin or arbor 56. Pivoted on such arbor 56 is a clapper lever 57 which is held in normal position by a spring wire 58, passing 35 through an opening in the arbor 56 and through an enlarged end or clapper 59 on such lever 57. Such clapper 59 is in the path of movement of a stud 60 which raises and releases the same against the tension of the spring 57, with the clapper 40 engaging and sounding the bell 46 when the last line for typing on the sheet is reached. Said stud 60 however, directly engages a flange 61 on an angular arm 62 of a trip lever 63 to sound the alarm. Such lever 63 as shown is pivoted on the arbor 56 45 and it has a hook 64 which is normally urged into engagement with a lug or wall 65 of the clapper lever 57, being so urged by means of a coil spring 66 fastened at one end to the arbor 56 and at its other end to the lever 63. It will be realized 50 that the levers 57 and 63 will raise and lower as a unit when engaged by the stud 60 moving in a clockwise direction and against the flange 61 to sound the bell 46 but that, when resetting, the stud 60 when moving against the flange 61 in a clockwise direction, will simply raise the lever 63 55 against the tension of its spring 66, in order to pass the same, without disturbing or operating the clapper or lever 57.

As a result of the construction described, when 60 a sheet of paper is placed in the typewriter in the usual manner, for instance with its upper edge even with the scale bar, it is known or calculated, at what distance the last line of the typewriting on the sheet should occur and the strip 47 is adjusted accordingly in connection with the calibrations 49 thereon and the zero indication 66 on the exterior of wall 16, the strip 47 remaining in the different adjusted positions by the frictional engagement of the same and 65 plate 50 with the wall 16. Such adjustment of

the strip properly locates the trip lever 63 and clapper lever 57 with respect to the stud 60. The usual rotation of the platen 11 according to the setting of the strip 47, will rotate the shafts 12 and 23, pinion 28, and gear 29, 5 gradually advancing the latter so that at the last line position for the typing, stud 60 will by anti-clockwise movement of the gear 30, strike flange 61, lifting levers 63 and 57 so that the striker or clapper 59 will fall against the bell 46 and thus 10 sound the alarm or signal that the last line for typing has been reached. In any intermediate or other position, as may be rendered necessary for erasing, back spacing or the like, the parts may be appropriately reset by depressing the lever 32, 15 against the tension of the spring 43-44, thereby disengaging the teeth 29 from those of the pinion 28, and thus enabling spring 35 to move the gear 30 clockwise to the extent permitted by abutment of the pin 39 with the stop spring 20 40 at the hooked end 42.

Various changes may be resorted to provided they fall within the spirit and scope of the invention.

I claim as my invention:

1. In combination with a rotatable platen, a gear rotatable through the rotation of said platen, an arbor on which said gear is journaled, a lever carrying said arbor, spring means urging the gear to normal position, said lever being movable to disengage the gear from driving relation with the platen so that said spring will reset the gear, a stud on said gear, a signal, means operable to actuate the signal through travel of said stud, comprising an indicator strip adjustable about the axis of the gear, a clapper lever carried by said indicator strip, and a trip lever carried by said indicator strip engageable by said stud to actuate the clapper lever.

2. In combination with a rotatable platen, a gear rotatable through the rotation of said platen, an arbor on which said gear is journaled, a lever carrying said arbor, spring means urging the gear to normal position, said lever being movable to disengage the gear from driving relation with the platen so that said spring will reset the gear, a stud on said gear, a signal, means operable to actuate the signal through travel of said stud, comprising an indicator strip adjustable about the axis of the gear, a clapper lever carried by said indicator strip, a trip lever carried by said indicator strip engageable by said stud to actuate the clapper lever, means mounting the trip lever for movement relatively to the clapper lever incidental to resetting of the device, and spring means engaging the first mentioned lever and urging it to set position.

3. In combination with a rotatable platen, a gear rotatable through the rotation of said platen, an arbor on which said gear is journaled, 60 spring means urging the gear to normal position, a stud on said gear, a signal, means operable to actuate the signal through travel of said stud comprising an indicator strip adjustable about the axis of the gear, a clapper lever carried by 65 said indicator strip, and a trip lever carried by said indicator strip engageable by said stud to actuate the clapper lever.

ADOLPHUS D. THOMAS.
